UNITED STATES PATENT OFFICE.

GUSTAF THEODORE NELSON, OF ORANGE, TEXAS, ASSIGNOR OF ONE-HALF TO OSCAR S. TAM, OF ORANGE, TEXAS.

SHAFT-COUPING.

1,305,925.

Specification of Letters Patent. Patented June 3, 1919.

Application filed December 23, 1918. Serial No. 267,984.

To all whom it may concern:

Be it known that I, GUSTAF T. NELSON, a citizen of the United States, and a resident of Orange, in the county of Orange and 5 State of Texas, have invented certain new and useful Improvements in Shaft-Couplings, of which the following is a specification.

My invention is an improvement in shaft 10 couplings, and has for its object to provide a device of the character specified primarily designed for installation on the shafting of steamships and the like, but applicable to installation on any line of shaft where the 15 line is not direct from drive to driven.

In the drawings:

Figure 1 is a side view of the improved coupling;

Figs. 2, 3 and 4 are longitudinal sections, 20 with the parts in different positions;

Fig. 5 is a transverse vertical section.

In the present embodiment of the invention a cylindrical block 1 is provided, having its ends recessed as shown at 2, the said recesses being square in cross section and rounded at their bottoms. Each of the sections 3 and 4 of the transmission shaft has a head 5 and 6, respectively, the said heads being square in cross section and having 25 their ends rounded to fit the bottoms of the recesses 2, and it will be noticed that each head tapers from near the rounded end to the shaft section. This permits lateral play in both directions, as will be evident from an 30 inspection of Figs. 2 and 4.

Each head has a transverse opening 7 and the openings of the heads taper from the center of the head toward the ends of the opening, gradually increasing in cross section toward the face of the head. A screw 8 40 is passed through each opening and through registering openings in the block 1, to connect the head to the block.

In operation, the squared surface of the recesses and the heads will take the strain of torsion, thus relieving the strain on the pin or screws 8, and the tapering of the openings 7 permits the sections to take the angular movement shown in Figs. 2 and 4 without pressure on the pin or screw. 45

In use, the sections may extend in alinement or they may take a position at an obtuse angle to each other, as shown in Fig. 2. They may also be inclined in opposite directions, as shown in Fig. 4, and whatever the 55 position or inclination of the shaft sections they may be made to assume a position with their long axes parallel or in alinement. 50

I claim:

1. A shaft coupling comprising a block 60 having recesses in its ends, said recesses being square in cross section and having rounded bottoms, the shaft sections having heads engaging the recesses and shaped to fit the same loosely, each head being tapered 65 toward the shaft section to permit angular movement of the shaft with respect to the block, and means connecting each head to the block, said means comprising pins extending transversely of the block and head, the opening in the head for the pin increasing in cross section toward each face of the head. 70

2. A shaft coupling comprising a block having recesses in its ends, said recesses being square in cross section and having 75 rounded bottoms, the shaft sections having heads engaging the recesses and shaped to fit the same loosely, each head being tapered toward the shaft section to permit angular movement of the shaft with respect to the 80 block, and means connecting each head to the block.

GUSTAF THEODORE NELSON.
